INTERNAL COMBUSTION ENGINE

Herbert C. Edwards, Detroit, Mich., assignor to
 Packard Motor Car Company, Detroit, Mich., a
 corporation of Michigan

Application March 31, 1932, Serial No. 602,233

8 Claims. (Cl. 123—31)

This invention relates to internal combustion engines and more particularly to mechanism for regulating the fuel charges introduced into engines of the Diesel type.

5 An object of the invention is to provide regulating mechanism for the fuel and air charges introduced into the cylinders of a Diesel type of engine which can be manipulated by the operator with little effort.

10 Another object of the invention is to provide a servo-control mechanism for assisting in the regulation of liquid fuel charges injected into the cylinders of Diesel type engines.

A further object of the invention is to provide 15 valve control mechanism for the air admitted to the cylinders of an internal combustion engine which can be actuated with very little manual effort through the assistance of a servo-device.

Still another object of the invention is to provide 20 a Diesel type of engine in which the quantity and timing of the fuel charges, and the temperature of air charges entering the cylinders is regulated through mechanism which includes a servo-device.

25 Another object of the invention resides in the provision of mechanism for a Diesel type of engine which can be regulated by a single manual operation to adjust the quantity of air introduced into the combustion chamber and the quantity 30 and time of the introduction of fuel charges introduced into the combustion chamber.

Other objects of the invention will appear from the following description taken in connection with the drawings, which form a part of this 35 specification, and in which:

Fig. 1 is a rear elevational view, partly in section and broken away, of a radial Diesel type of engine with which my invention is associated;

Fig. 2 is a sectional view taken on line 2—2 40 of Fig. 3 showing the details of the servo-control device;

Fig. 3 is a sectional view through the servo-device taken on line 3—3 of Fig. 2;

Fig. 4 is another sectional view of the servo-device taken on line 4—4 of Fig. 2;

Fig. 5 is still another sectional view of the servo-device taken on line 5—5 of Fig. 2;

Fig. 6 is an elevational view of the servo-device;

50 Fig. 7 is a sectional view of the servo-device taken on line 7—7 of Fig. 2;

Fig. 8 is a longitudinal section of the plunger forming a part of the servo-device taken on line 8—8 of Fig. 4;

55 Fig. 9 is another longitudinal section of the

plunger of the servo-device taken on line 9—9 of Fig. 4;

Fig. 10 is a fragmentary sectional view taken on line 10—10 of Fig. 1 illustrating a portion of the air valve regulating mechanism;

Fig. 11 is a fragmentary end view, partly in section, of one of the cylinders and the associated control mechanism for the air valve;

Fig. 12 is a sectional view of the nozzle portion of one of the injection devices associated with 10 a fragment of a cylinder;

Fig. 13 is a sectional view of a fragment of the servo-device taken on line 13—13 of Fig. 6;

Referring to the drawings wherein I have shown my invention associated with a radial type 15 of Diesel engine, 10 indicates a drum-like crank case, having its rear end enclosed by a removable cover 11, from which a plurality of cylinders 12 project radially. The cylinders are provided with oppositely disposed flanges, as indicated at 13, 20 which rest against the flat portions of the outer surface of the crank case, and a pair of compression rings 14 encircle such flanges and secure the cylinders with the crank case.

The cylinders are each formed with an integral 25 dome 15 upon each of which is fixed a head 16. Extending through the dome and head of each cylinder is a Venturi passage 17 which is arranged to extend at an angle to the cylinder axis and tangentially of the inner wall thereof. Each of 30 such passages provide both the air inlet and the exhaust outlet, and they each communicate at their outer end with a conduit 18 which extends transversely thereof and axially in the direction in which the engine moves in its travel when 35 utilized as the power plant for an aeroplane. The passages are each controlled by a poppet valve 19, the stem portions of which extend into housings in the heads and are opened by suitable mechanisms extending through rotatable sleeves 20 and 40 into the crank case where they are actuated by the cam 21. A plurality of springs, as indicated at 22, serve to normally maintain the valves in closed position.

The engine illustrated is of the four cycle type, 45 and the valves are maintained in open position during the exhaust and intake strokes of the pistons, which are contained within the cylinders and connected with the crank shaft 23 in the usual manner, and in closed position during the 50 compression and power strokes of the pistons.

At the forward end of each conduit 18 there is pivoted a valve 24 from which an arm 25 extends. Such arms have control rods 26 connected thereto which are actuated by levers 27 to open and 55

close the valves. A spring-pressed abutment 28 is carried by each conduit and is associated with the valve thereof to normally retain the same in wide open position after being moved into such relation. The valves 24, as shown in Fig. 11, can be moved to wide open position or to a position closing the air inlet end of the conduits when moved to the position shown in dotted lines, and the valve can be regulated so that they will be located in any relation intermediate the two extreme positions mentioned. The levers 27 are formed as a part of the collars 29 which are fixed upon the rotatable sleeves 20 and the position of the valves is adjusted through rotation of such sleeves.

In order to simultaneously regulate the valves 24, a ring 30 is arranged adjacent the sleeves 20 and is provided with arms 31, one adjacent each sleeve, and such arms engage with an arm 32 projecting from collars 33 secured one to each of the sleeves 20. By rotating the ring 30 the sleeves will be rotated and the valves will be adjusted. This valve regulating mechanism is preferably associated to be actuated by and in a definite relation with the mechanism for regulating the volume in the liquid fuel charges which is injected in the cylinders. Brackets 34 are secured to the control ring 30 and engage with bosses on the crank case to guide and retain the ring in position with the engine.

An injection device is associated with each cylinder and as they are similar and include generally a nozzle section and a pump section, a description of one will suffice for all. The nozzle casing 35 is formed with a neck 36 upon which the pump casing 37 is secured so that the injection device is an integral unit which can be attached or detached from its associated cylinder. An extension casing 38 is screwed into one end and a plug 39 is screwed into the other end of the nozzle casing. The casing extension is formed to extend into an opening 40 in the cylinder wall and flanges 41 extend therefrom and are secured to the cylinder by bolts 42, best shown in Fig. 1. Valves 43 extend through a passage formed axially in the nozzle casing and extension, and the head 44 of the valve is arranged to co-operate with a flared outlet end of the nozzle extension passage. Spring retainer and bearing means is secured to the end of the valves within the passage in the nozzle casing and the valve is normally urged away from the axis of the cylinder by a spring 45. An adjustable stop member 46 extends through the plug 39 to limit the closing movement of the valve so that the circular edge of the head thereof will not strike the passage wall. The spring retainer is provided with axially extending passages 47 and the valve stem is provided with axially extending passages 48 so that fuel can travel from the passage 49, in the nozzle neck, through the outlet passage in the nozzle extension.

Within the pump casing 37 is seated a barrel 50 in which the pump plunger 51 is arranged to reciprocate, there being a guide 52 mounted in the nozzle casing, exteriorly of the barrel, with which an end of the plunger is connected and normally urging this guide and plunger in a direction away from the associated nozzle is a coil spring 53. The valve communicates with the passage 49 and a check valve 54 is arranged between the barrel and nozzle to prevent return of fuel from the nozzle back to the pump barrel. A circular housing 55 is wedged upon the pump casing

and is secured by a nut 56, and radially extending ports 57 extend through the barrel and the pump casing and are in open communication with the space within the housing 55. A conduit section 58 connects each of the adjacent housings 55, and liquid fuel from a source of supply is maintained under low pressure in such conduit sections and housings so that when the plungers 51 uncover the ports 57, fuel flows into the barrels maintaining them completely filled.

Prior to closing the ports 57, movement of the plungers 51 toward the nozzles will force fuel back into the manifold housings 55 and conduit sections 58, whereupon the remaining fluid in the barrels will be trapped and displaced through the nozzles upon further movement of the plunger in the direction of the nozzle. The volume of the fuel charge delivered upon each stroke of the plunger depends upon the axial movement thereof after closing the ports 57, and it will be understood that during the injection period the pressure upon the fluid in the nozzle will be extremely high and will force the valve head 44 toward the axis of the associated cylinder.

A bearing sleeve 59 extends through the crank case adjacent each cylinder and a section 60 of an articulated push rod is guided therein. An adjustable bolt 61 is associated with the outer end of each of the push rod sections 60 and engages with the plunger guide members 52. Pivottally associated with the push rod sections 60 is another section 62, and such sections bear against the free ends of rock levers 63 mounted upon pins 64 which are mounted in the crank case end wall 11 and a diaphragm 65 within the crank case. The push rod bearing ends of the levers are curved normal to their axis of their pivots and adjustment of the push rod sections longitudinally of the rock levers along such curved surfaces will regulate the time at which ports 57 are closed and the length of the stroke of the plungers after closing the ports. For simultaneously regulating the position of the push rod sections 62 on their curved bearing surfaces, there is a ring 66 which is carried by the diaphragm wall 65 through means of bolts 67 which extend through arcuate slots 68 in the ring and are screwed into the diaphragm wall. Links 69 connect the push rod sections 62 with the ring. Upon rotation of the ring, the push rod sections will be moved longitudinally of the curved surfaces at the free end of the rock levers to regulate the quantity of and the time at which fuel is projected from the nozzles by the plungers.

In order to rotate the ring 66, I fix a rack member 70 thereon and in mesh therewith is a gear on a yoke 71 mounted on a shaft 72.

The cam 21 is arranged within the compartment, between the end wall 11 and the diaphragm wall 65, into which the push rods extend and which also contains the control ring 66. This cam is provided with four similar lobes 73 which are arranged to engage with the rock levers 63. Reduction gearing is interposed between the crank shaft and the cam and consists of a gear 74 fixed to the crank shaft, another gear 75 meshing therewith and carried by the shaft 76 which is mounted in the end wall, a gear 77 which is also fixed to the shaft 76 and which meshes with the internal gear 78 formed on the cam. The engine illustrated is provided with nine cylinders and the gear reduction between the crank shaft and the cam is such that the cam is driven in an anti-clockwise direction looking at the rear and at

one-eighth crank shaft speed so that upon each two revolutions of the crank shaft each of the rock levers 63 will be actuated to cause an injection from each of the nozzles associated therewith.

In order to regulate both the control rings 66 and 30, I provide servo-mechanism which is associated with the engine lubricating system. To this end, a cylinder 80 is secured to the diaphragm 65 and is provided with an oil inlet port 81 which is connected with the engine pressure lubricating system by means of a conduit 82 provided in the cylinder supporting bracket 83. The engine lubricating system is arranged to lead into the passage 84 in the diaphragm, for example as shown in the patent to Lionel M. Woolson, 1,903,411, April 4, 1933, and an outlet 85 is provided in the cylinder and opens directly into the crank case.

Within the cylinder is arranged a plunger element consisting of a central body portion 86 and two end portions 87 and 88, the end portion 88 being formed with a sleeve 89 which extends through the bearing 90 at one end of the cylinder. Another sleeve 91 is arranged to telescope into the sleeve 89 and threaded therein is a shaft 92 which extends into the cylinder and through the piston structure. The other end of this shaft 92 has an extension 93, detachably secured therewith, which is arranged to slide through a bearing 94 formed on one end of the cylinder. Within the last mentioned bearing is a packing ring 95 which is compressed by a nut 96 screwed into the end of the bearing, such nut being hollow so that the shaft extension 93 can slide therein. The purpose of the shaft extension 93 and its arrangement with the packing is to provide resistance to free movement of the shaft 92 in the cylinder. The piston sections are secured together by a plurality of axially extending bolts, as indicated at 97. Each end of the central section 86 of the piston structure is formed with a pair of separate chambers which extend in a plane transversely to the piston axis, one of the chambers 98 at each end of the piston serves as an inlet while the other chamber 99, at each end of the piston, serves as an outlet. Extending in an axial direction through each of the end sections of the piston is a port 100 which is arranged to establish open communication between the outlet chamber 99 and the end of the cylinder.

The piston end sections are also provided with suitable rings, as indicated at 102, to prevent leakage around the cylinder engaging portion thereof. The central section of the piston structure is formed with a pair of saw-cuts forming chambers 103 which extend into the periphery a short distance in spaced relation axially and which slightly overlie each other axially of the piston so that they each communicate with a longitudinally extending recess 104 formed in the central piston section and extending axially thereof, this recess being arranged so that it communicates with the outlet port 85 in the cylinder and chambers 103 being arranged so that they each communicate with an outlet chamber 99. The central portion of the piston is also formed with a similar pair of saw-cuts in the periphery thereof, opposite the saw-cuts 103, forming chambers 105 which are in spaced relation axially of the piston and in open communication with a recess 106 which extends in an axial direction along the periphery of the central section of the piston. The recess 106 is arranged to register with the inlet port 81 in the cylinder, and the chambers 105

are in open communication with the chambers 98.

Valves, as indicated at 106', are arranged to co-operate with seats 107 in order to control the passage of fluid between the chambers 98 and 106, such valves extending in opposite directions. Another pair of valves 108 are arranged to co-operate with seats 109 formed in the central piston section in order to control flow of fluid between the outlet chambers 103 and 99.

The valve position is controlled by the rod 92 and on such rod I provide arms 110 and 111 which are located in recesses formed in the piston so that they can reciprocate with the shaft 92. The arm 110 is provided with adjustable tappets 112 which are arranged to align with the ends of the pair of valves associated with the opposite end of the piston and the arm 111 carries adjustable tappets 113 which are arranged to align with the valve ends 108 and 106' for the other end of the piston structure. Surrounding each of the valve stem ends is a coil spring 114 which seats at one end against the piston and at the other end engages a retainer 115 fixed adjacent the end of each of the stems, such springs normally tending to move the valves into a closed position with their seats. The tappets are set close to the valve ends so that a very short movement of the rod and arms is required in order to open the valves and thus the valves are actuated by a short movement of the rod 91. In order that the rod 91 can be actuated to move the piston structure manually, I provide shoulders 116 with which the arms 111 and 112 engage upon a short movement of the rod 91.

The outlet chamber 99 at each end of the piston structure communicates with the inlet chamber at the opposite end of the piston structure through means of axially extending passages 117 extending through the central piston section and surrounding two of the bolts 97.

A bearing 120 extends through the crank case 10 and is clamped to the crank case by a nut 121. Projecting through the bearing is a sleeve 122 and carried by the sleeve is the shaft 72. To the outer end of the shaft is fixed an arm 124 having an end 125 to which suitable mechanism, as indicated at 125', can be fixed for rotating the arm remotely from the end. Both the shaft 123 and the sleeve 122 are freely rotatable relatively, and relative to the bearing 120. The yoke member 71 is formed at one end with tongues 126 which extend into complementary recesses in the inner end of the sleeve 122.

The shaft 92 is threaded into the sleeve 91 and projects beyond the end thereof, such sleeve being also telescoped within the sleeve 89 and projecting beyond its end. A pin 127 extends through the projecting end of the sleeve 91 and pivotally mounted on such pin is a link 128. The other end of this link extends between the arms of a yoke 129, which is pressed onto the end of shaft 72, and the link 128 and yoke 129 are pivotally connected by the pin 130. The arms of the yoke 71 have pivot members 131 extending therethrough and pivotally mounted on such pivot members is a U-shaped link 132. Threaded upon the projecting end of the sleeve 89 is an extension 133 pivoted on the pins 131 carried by one end of the sides of the link 132. The other end of the sides of the arms of the link 132 are mounted upon pins 135 which are fixed to arms 136 projecting from the gear segment yoke 71.

The arm 124 is arranged with relation to the engine so that the forward or rearward movement of the extended operating mechanism as-

sociated therewith will cause rotation of the shaft 72. Such movement of the shaft 72 will rotate therewith the yoke 129 which in turn will impart movement to the link 128 which is transmitted through the pin 127 to reciprocate the sleeve 91, and as this sleeve is fixed to the shaft 92, the arms 110 and 111 will be moved in an axial direction in the cylinder 80.

When the shaft 92 is moved toward the bottom end of the cylinder, as shown in Figs. 2 and 7, the tappets 112 on the arm 110 will engage the stem ends of the valves 106' and 108 at the upper end of the piston and will move them toward the bottom end of the cylinder establishing communication between the lower inlet chamber 105 and the adjacent chamber 98. Oil from the pressure lubricating system will thus be free to move through the port 81 in the cylinder, the open inlet chamber 105 and into the chamber 98. Such oil flow passes from the chamber 98 axially of the piston through the port 117 and into the upper exhaust chamber 99 from which it flows through the port 100 into the upper end of the cylinder and thereby exerts a downward pressure against the piston causing it to move with the rod 91 toward the bottom of the cylinder. While the lower inlet valve 106' is thus held open, the outlet valve at the lower end of the piston is also held open and fluid in the bottom end of the cylinder can flow through the port 101 and the outlet chambers 99 and 103 and thence into the recess 104 and through the outlet port 85 in the cylinder. The outlet port 85 opens directly into the crank case and the oil drops to the bottom thereof along with that which has escaped from the bearings within the crank case and is recirculated in the lubricating system in the usual manner. The port 81 is always in open communication with the lubricating system through conduit means previously described so that whenever either one of the inlet valves 106' is open, oil from the lubricating system is free to flow into one or the other end of the cylinder because the inlet passages 105 are always in communication with the port 81 through the axially extending recess 106' formed in the periphery of the piston. The exhaust port 85 is always in open communication with the outlet chambers 103 even though they are in different axial planes for the reason that there is a space between the cylinder wall and the chambers 103 formed by the recess 104 and whenever the valves 108 are open, there will be a flow from one end or the other of the cylinder through the port 85.

Upward movement of the shaft 92 will open the valves at the upper end of the piston and similar flow of fluid will pass through the cylinder and the piston structure in a similar but reverse manner as that just previously described. In this manner, rotation of the shaft 72 will take only sufficient energy to move the arm 110 or 111 into a position opening the adjacent valves, whereupon there will be a corresponding movement of the piston effected by the lubricating system so that very little manual effort is required in order to move the piston within the cylinder. Friction of the bearing member 95 against the shaft extension 93 is sufficient to take up lost motion in the mechanism and to prevent creeping thereof. The tappets 112 and 113 are adjusted so that very little movement of the bars 110 and 111 is required in order to open the associated valves which also tends to decrease the amount of manual effort required before the hydraulic or servo-action takes place.

When starting the engine, there is of course no pressure in the lubricating system and hand operation of the mechanism is resisted by the high vacuum in the cylinder. In order to overcome this resistance to manual operation of the mechanism, I provide the passage 140 which extends substantially normal to and in communication with the passage 82 in the supporting bracket 83, and into the outer end of this passage 140 I provide an air inlet cap 141. A one way ball valve 142 is arranged within the inlet member 141 and is normally held to close the port 143 by means of a spring 144. When there is pressure in the passage 82, it will maintain the valve 142 in closed position so that there can be no entrance of air, but when there is a vacuum in the cylinder, then air is free to flow into the cylinder and thereby reduces the vacuum so that vacuum resistance to manual operation is substantially reduced.

As the sleeve 89 is formed as an integral part of an end section of the piston, it will reciprocate with the piston and in so doing will impart similar movement to the yoke extension 133 and through means of the pins 131, this motion being transmitted to the link 132 which transmits rotation to the gear segment yoke 71 through the pin connections 135. Rotation of the gear yoke 71 is imparted to the rack 70 which is fixed to the ring 66 and is also imparted to the sleeve 122 through means of the association of tongues 126 with the recesses in the sleeve.

It will thus be seen that the sleeve 122 and the ring 66 are both responsive to reciprocatory movement of the piston. As previously described, rotation of the ring 66 through means of the links 69 will change the position of the push rod sections 62 longitudinally on the curved surface of the rock levers 63 so that the strokes imparted thereby to the pistons 51, when actuated by the cam, are adjusted. The rock levers are raised and lowered the same distance at all times by the cam 73 and adjustment of the push rod sections 62 along the surfaces of the rock levers toward and away from the rock lever pivots will vary the length of the stroke of the push rods. When the push rod sections are nearest the pivots 64, then the stroke imparted to the plungers 51 will be shortest and, when the push rod sections are nearest the free end of the rock levers, then the stroke imparted to the plungers 51 will be the longest. In this manner, the axial movement of the plungers after closing the ports 57 determines the fuel quantity delivered from the nozzles into the cylinders and, when the stroke is shortest, the ports 57 will not be closed and, under such circumstances, the engine will not operate as there is no fuel delivered. As the stroke of the plungers is increased, then the time at which they close the ports 57 is advanced and vice versa so that the time at which fuel is delivered into the combustion chambers and the quantity thereof are regulated simultaneously by the adjustment of the push rod sections 62 upon rotation of the ring 66 and the movement of the connecting links 69.

As shown in Fig. 1, the push rod sections 62 are at one extreme of their adjustment and in such position the pumps operated thereby will inject maximum fuel charges. When the ring 66 is in a position to place the push rod sections 62 in relation with the rock levers 63, as shown in Fig. 1, the piston will be in one extreme position within the cylinder, as shown in Fig. 2, and when the ring 66 is moved to lock the push rods 62 in

the other extreme position on rock levers 63, then the piston in the cylinder must be at the lower end of the cylinder, as shown in Fig. 7. It therefore follows that in order to move the ring 5 in a direction to increase the fuel quantity, then it is necessary to open the valves seated at the upper end of the piston, as shown in Fig. 7, and when it is desired to reduce the quantity of fuel delivered in the charges, then the rod 92 must 10 be moved in a direction to open the valves at the lower end of the piston or the bottom valves, shown in Fig. 2. When the manual effort exerted against the arm 124 ceases, the valve springs will 15 close the valves which have been held open by the manual effort and the piston will remain stationary at such point in the cylinder so that, in this way, any desired adjustment is maintained as there can be no flow through the piston because the valves at both ends thereof are 20 closed.

Occasionally in the operation of an engine of this type, it is desirable to move the fuel charge regulating ring 66 faster than the servo-mechanism will operate and, under such circumstances, 25 the fast movement of the rod 92 will cause the one or the other of the bars 110 or 111 to engage against the adjacent shoulder 116 formed of the piston structure, depending upon the direction of the shaft movement, and such engagement will allow the piston to be moved manually 30 as quickly as may be desired. It will therefore be seen that in case of emergency or when desired, the fuel adjusting ring 66 and the mechanism associated therewith can be operated entirely 35 by hand.

As previously related, the sleeve 122 is rotated with the gear segment yoke 71, and carried by the outer end of the sleeve is a roller 145 which is located to engage in a recess 146 formed in an 40 arm 147 fixed to one of the push rod housings 20. The arm 32 on each of the push rod sleeves 20 has a ball shaped end 149 engaged in a socket formed in the associated arm 31 fixed to the ring 30. On each of the sleeves 20 there is also fixed 45 the arm 27, previously described, for operating the associated arm 26 and valve 24. It will therefore be seen that rotation of the sleeve 122 will rock the roller 145 which engages with the arm 147 and rotates the associated push rod sleeve 50 20 so that the arm 32 associated therewith will give the ring 30 rotational movement and thus rotate all of the other push rod sleeves 20 uniformly and simultaneously.

The purpose of the valves 24 is to control the 55 quantity of air flowing into the engine from atmosphere as Diesel engines have certain characteristics where it is desirable to regulate the quantity of fresh air in a definite way relative to the amount of fuel being delivered in the 60 charges. For example, when the engine is cold in starting up it is more desirable that very little fresh air be drawn into the cylinders because it tends to lower the temperature and as temperature is relied upon for ignition these valves being 65 closed, or nearly so, assist in quick starting. Likewise when an engine is utilized as a power plant of an aeroplane, the fuel supply is normally reduced to an idling condition when the aeroplane is gliding and under such circumstances 70 only a very small quantity of fresh air can be drawn into the cylinders, or otherwise the temperature of the air tends to chill the cylinders and causes stalling. In order, therefore, that the valves may be regulated as most desirable for 75 the operation of Diesel engines of the class de-

scribed, the arm 147 is formed with a slot 146 so that the association therewith of the roller 145 in its rotation will cause the valves to be substantially closed under 600 R. P. M. and to quickly move the valves to wide open position at substantially 1400 R. P. M. The shape of the recess can be formed to produce different valve opening and closing conditions as are most desirable, but the operation specified above has been selected by way of illustration because the engine herein described idles below 600 R. P. M. and rotates at a sufficient speed to maintain flight of an aeroplane above 1400 R. P. M. Between 600 and 1400 engine R. P. M. the air valves will be gradually opened or closed simultaneously with and in accordance with the regulation of the quantity of fuel in the charges and the time at which such charges are delivered into the combustion chambers. Thus it will be seen that within a predetermined range of adjustment the mechanism 20 can be manually controlled to simultaneously regulate the air and fuel quantity in the charges and the time at which the same is injected into the engine combustion chambers so that, as the quantity is reduced and the timing retarded, the air quantity flowing into the cylinders will likewise be reduced and vice versa.

When the roller 145 is in engagement with the face 150 forming one end of the recess, the valves will be in the position shown in dotted lines in Fig. 11 and when the roller has been moved to contact with the face 151 of the recess, the valves will have been moved to the position shown in full lines in Fig. 11. Between the faces 150 and 30 151 there is an adjacent sharply recessed face and a straight face so that when the roller 145 leaves the face 150 or 151, it will cause a quick movement of the arm 147 after which follows a slower movement as the roller moves along the straight face so that, in this manner, the rods 40 26 will be given a fast movement adjacent each end of their range and a slower movement during the middle portion of their range of movement and thus the valves will move quickly immediately upon leaving or approaching closed or wide open position.

The mechanism herein described is of a servo-character and therefore very little manual effort is required to simultaneously control the volume 50 and timing of the fuel charges injected into the cylinders and the position of the air inlet valves at the entrance end of the conduits 18. The control mechanism described is compact and sensitive and, in addition, it can be actuated manually at will.

Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. In an internal combustion engine in which fuel and air charges are regulated by separate control mechanisms, means for actuating said mechanisms comprising a physically rotatable shaft, a sleeve rotatably mounted on said shaft and connected to regulate said air charge control mechanism, a rotatably mounted yoke connected to regulate said fuel charge control mechanism, a driving connection between said sleeve and said yoke, and a driving connection between said shaft and said yoke.

2. In an internal combustion engine in which fuel and air charges are regulated by separate control mechanisms, means for actuating said mechanisms comprising a physically operable shaft, a sleeve rotatable on said shaft connected to actuate said air regulating mechanism, a servomotor connected to be controlled by said shaft, a yoke connected to actuate said fuel control mechanism, said yoke being connected in driving relation with said sleeve, and actuator mechanism connecting said servo-motor with said yoke.
3. In an internal combustion engine in which fuel and air charges are regulated by separate control mechanisms, means for actuating said mechanisms comprising a physically operable shaft, a sleeve rotatable on said shaft connected to actuate said air regulating mechanism, a servomotor connected to be controlled by said shaft, a yoke connected to actuate said fuel control mechanism, said yoke being rotatably mounted on said shaft, and actuator mechanism connecting said servo-motor with said yoke.
4. In an internal combustion engine, mechanism for simultaneously adjusting injection devices to regulate fuel charges introduced into a plurality of cylinders, a physically rotatable shaft, a rotatably mounted yoke connected in driving relation with said adjusting mechanism, and mechanism including a servo-motor connecting said shaft in operative relation with said yoke.
5. In an internal combustion engine, mechanism for simultaneously adjusting valves to regulate air charges introduced into a plurality of cylinders, a physically rotatable shaft, a sleeve rotatably mounted on said shaft and connected in driving relation with said valve adjusting mechanism, an element connected in driving relation with said sleeve, and a driving connection from said shaft to said element including a servo-motor.
6. In an internal combustion engine having a ring within the crank case for simultaneously regulating the effective stroke of fuel injection devices and a ring exterior of the crank case for simultaneously regulating a plurality of air charged control valves, regulating mechanism for said rings comprising a physically rotatable shaft extending through the wall of the crank case, a sleeve rotatably mounted on said shaft and extending through the crank case wall, a driving connection between said valve regulating ring and said sleeve, an element rotatably mounted on said shaft and keyed to said sleeve, said element lying within said crank case, a driving connection between said fuel injection regulating ring and said element, and a driving connection in said crank case between said shaft and said element including a servo-motor.
7. In an internal combustion engine, mechanism for simultaneously adjusting valves to regulate air charges introduced into a plurality of cylinders, a physically rotatable shaft, a sleeve rotatably mounted on said shaft, a lost motion connection between said sleeve and said valve adjusting mechanism, an element rotatably mounted on said shaft in driving relation with said sleeve, and a driving connection from said shaft to said element including a servo-motor.
8. In an internal combustion engine in which the air charges are regulated by separate control mechanisms, means for actuating said mechanisms comprising a physically rotatable shaft, a sleeve rotatably mounted on said shaft and connected to regulate said air charge control mechanism, a rotatably mounted element in driving relation with said sleeve and connected to regulate said fuel charge control mechanism, a servo-motor having a stationary part and control and actuator elements, a connection between said shaft and said servo-motor control element, and a connection between said servo-motor actuator element and said rotatable element connected with the mechanism for regulating the fuel charges.

HERBERT C. EDWARDS.
